UNITED STATES PATENT OFFICE.

RUDOLPH F. BARTEL, OF NEW YORK, N. Y.

GARTER.

Application filed September 30, 1921. Serial No. 504,393.

This invention relates to an improved garter characterized by a construction that avoids any metal or projecting parts coming in contact with the limb of the wearer or his garments.

The object of the invention is the production of a garter that can be easily secured in place. Another object of the improved garter is to be enabled to clamp a stocking 10 at variable distances from its top edge. A third object of the invention is the production of a garter that has extending therefrom a depending strap with a clamping device which is below and directly in line, 15 with a clamping device that connects the ends of the leg band of the garter. By means of this construction the strains on the leg band are transmitted through its clamping device and thereby the strains on each 20 side of said clamping device are equalized.

In the accompanying drawings which represent an exemplification of one form of the improved garter Fig. 1 shows a front elevation thereof with its leg band in perspective; Fig. 2 represents an enlarged section of Fig. 1 on the line 2, 2; Fig. 3 shows an enlarged section of Fig. 1 on the line 3, 3 and Fig. 4 indicates an enlarged section of Fig. 1 on the line 2, 4 with the hook end of the leg band locked in operative position.

The garter comprises the leg band 20, in this instance of elastic webbing of one continuous piece of material with the hook end 21 and the disc end 22. A slide buckle 23 is provided for the band 20 to adjust its length at one end portion thereof. At the extreme outer end of the adjusted portion is secured a frame 24 with the hook 25. At the other end of the leg band 20 is fastened a double disc designated in its entirety by the letter A. The said disc comprises the outer member 26 that has connected thereto the eyelet 27 and the inner member 28 with the inner face 29. The said disc is preferably made of pliable material and the members thereof are connected to each other by the stitching 31, forming a pocket 32 between them. The disc has secured thereto the end 22 of the leg band 20. The said disc extends above the top edge and below the bottom edge of the leg band 20 and forms a complete enclosure for the pocket 32.

A depending strap designated in its entirety by the letter B, has its top end connected to the disc A by the stitching 31. 55 The said strap comprises the pair of members 35, 36 and the pair of members 37, 38. The members 37 and 38 at their lower end join to form a loop 39, for the loop 40. The members 35 and 36 form a loop 43 at their 60 bottom ends and the member 36 supports the button 45. It will be noted that the two pairs of members 35, 36 and 37, 38 are only connected to each other at their top ends by the stitching 31 in the disc A. 65

To secure a garter, in position the leg band 20 is located around the limb of the wearer or around the garment thereon and the hook end 21 is located over the disc A and the hook 25 locked into the opening of 70 the eyelet 27. The upper portion of the stocking which is to be supported is then located between the members 36 and 37 of the strap B, and by reason of the fact that 75 said members are only connected to each other at their top ends, the top edge of the stocking can be located at different distances from the top end of said strap B. The stocking is now clamped over the button 45 by means of the loop 40 in the usual manner. 80

It will be noted by an inspection of Fig. 4 that when the hook 25 is locked to the eyelet 27, its outer end is located adjacent to the inner face 29 of the inner member 28 of the disc A, thereby avoiding any contact of said 85 hook with the wearer.

It will also be noted that the button 45 is in a vertical line directly below the eyelet 27, by reason of which the strains on the ends 21 and 22 of the leg band are equalized. 90

Having described my invention what I desire to secure by Letters Patent and claim is:—

In a garter the combination of a leg band of one continuous piece of material, means to adjust the length of the band at one end portion thereof, a hook extending from the extreme outer end of said adjusted portion, a disc of pliable material connected to the other end of the band and extending above the upper edge and below the lower edge thereof, the said disc comprising an outer member and an inner member stitched to each other completely around their circumfer- 95 100

tial edges to form a complete enclosure to constitute a pocket between them, an eyelet extending through an opening in the outer member of the disc and fastened thereto, 5 said hook adapted to lock with the eyelet and extending therethrough into said pocket, a strap comprising members of webbing

extending from the disc and a button with a loop carried by said strap.

Signed at the borough of Manhattan, city 10 of New York, in the county of New York and State of New York this 26th day of September, A. D. 1921.

RUDOLPH F. BARTEL.
